CLAIM

The ornamental design for an adapter, as shown and described.

DESCRIPTION

FIG. 1 is a perspective view of an adapter showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing the adapter with a first type of plug;

FIG. 9 is second perspective view showing the adapter with a second type of plug; and,

FIG. 10 is third perspective view showing the adapter with a third type of plug.

The broken lines immediately adjacent to the shaded area define the bounds of the claimed design, and form no part thereof. The broken lines showing the remainder of the adapter, and alternate plugs in FIGS. 8-10, are for environmental purposes only, and form no part of the claimed design.
